(57) **CLAIM**

The ornamental design for a diagnostic device with LED display, as shown and described.

DESCRIPTION

FIG. 1 is a top front perspective view of a diagnostic device with LED display;

FIG. 2 is a front view of the diagnostic device with LED display;

FIG. 3 is a rear view of the diagnostic device with LED display;

FIG. 4 is a right side view of the diagnostic device with LED display;

FIG. 5 is a left side view of the diagnostic device with LED display;

FIG. 6 is a top view of the diagnostic device with LED display; and,

FIG. 7 is a bottom view of the diagnostic device with LED display.

The broken lines depicting the indicia in FIGS. 1 and 6 represent the environment and form no part of the claimed design, and the remaining broken lines illustrate portions of the diagnostic device with LED display that form no part of the claimed design.
